UNITED STATES PATENT OFFICE

2,383,159

TYPOGRAPHICAL MACHINE

James C. Plastaras, Laurelton, N. Y., assignor to
Mergenthaler Linotype Company, a corporation
of New York

Application December 17, 1941, Serial No. 423,262

28 Claims. (Cl. 199—46)

This invention relates to typographical machines, such as "Linotype" machines of the general organization represented in Letters Patent of the United States, No. 436,532, to O. Mergenthaler, wherein circulating matrices are released from a magazine in the order in which their characters are to appear in print and then assembled in line, the composed line transferred to the face of a mold, the mold filled with molten metal to form a slug or "Linotype" against the matrices which produce the type characters thereon, and the matrices thereafter elevated and returned through distributing mechanism to the magazine from which they started.

More particularly, it relates to machines equipped with a plurality of superposed magazines containing different matrix fonts and which are arranged to be moved as a unit upwardly and downwardly in the machine to bring one or another into operative relation to the assembling and distributing mechanisms. In such machines, the magazines are independently removable and replaceable and, to this end, are arranged to be spread apart in order to permit access to the magazine to be removed which, for this purpose, is first located in operative position. Provision is also made for raising the magazine to be removed on its supporting base frame clear of the assembler throat, so that it may be drawn forwardly by the operator and supported in a vertical position at the front of the machine by arms pivotally arranged on the machine frame and adapted to be swung into a position to support the magazine in the manner stated. The replacement of a magazine is effected by reversing these operations.

The pivotally mounted supporting arms are permanently secured to the machine frame and normally located in an inoperative position alongside of the bank of magazines. As the magazine to be removed is located in operative position, mechanism associated therewith is automatically brought into operative relation to devices operated by one of the pivoted arms, so that, as the arm is swung forwardly into active magazine supporting position at the front of the machine, such magazine (i. e., the one to be removed) will be lifted to separate it from its base frame and locate it in a position to clear the assembler devices during its removal from the machine. And likewise, in the case of a replacement magazine, the return movement of the pivoted arm to inactive position will lower such magazine into the base frame, for proper location with respect to its assembler devices.

Also, safety elements are provided for locking the pivoted arm against movement until the magazines have been properly spread to permit the removal of the selected magazine; and other elements are provided for locking the magazines to their base frames, the latter locking element being released by the initial movement of the pivoted arm from inactive position and being reset in locking position by the final return movement of the arm to inactive position.

According to the present improvements, there is provided a magazine spreading attachment which is entirely automatic insofar as concerns the selection of the magazines to be spread apart for the removal of the magazine in operative position. In other words, regardless of which magazine is in operative position, the operation of the device will cause all the overlying magazines, whether there be one, two or three, to be spread apart from said operative magazine and this without any thought upon the part of the operator. To this end, the base frames are provided at their opposite sides with laterally extending lugs adapted to be engaged by a pair of vertically movable arms for spreading the magazines apart. The arms are mounted, one at each end of a transverse rock shaft, and extend upwardly along the opposite sides of the bank of magazines rearward of the lugs. The rock shaft and magazine spreading arms are mounted in the machine frame independently of the bank of magazines, and a hand crank fixed to the rock shaft is operable by forward rotation, first to move the arms into engagement with the lugs on the base frame of the magazine (or magazines) above the one in operative position, and then to lift the arms vertically for spreading the magazines. The arms are formed on their forward edges with a series of lugs (three for a bank of four magazines) arranged to engage beneath the laterally projecting lugs on the base frames, the lugs on the arms being spaced apart so that, as the arms move vertically, the magazines will be lifted and spread progressively, starting with the top-most magazine.

The present improvements also contemplate a novel linkage between the pivoted magazine supporting arm and the device for raising the operative magazine from its base frame preparatory to removal and for lowering the replacement magazine back into position on the base frame. The improved construction gives an increased mechanical advantage which greatly facilitates the operation.

The magazine base frames have also been substantially improved. Heretofore, they were made of iron cast in a single heavy structure comprising marginal members and intermarginal crosspieces to provide reinforcement for the marginal members as well as supporting elements for the magazine and associated mechanisms. Such cast base frames were necessarily extremely heavy in order to provide the required strength for carrying out their intended functions. These heavy units were difficult to handle during the machining and finishing processes and were susceptible to breakage because of the essential brittleness of cast iron. Furthermore, if such castings are inaccurately formed or improperly finished in some respect, the entire unit might be rendered useless.

According to the present invention, the magazine base frame is built up of structural steel shapes assembled and joined together, preferably by welding, to provide a sturdy but very light, open structure.

These and other features of the present invention will be more fully described in the detailed description to follow.

In the accompanying drawings, the invention has been shown merely by way of example and in preferred form, and obviously many variations and modifications thereof may be made which will still be comprised within its spirit. It is to be understood, therefore, that the invention is not limited to any particular form or embodiment except insofar as such limitations are specified in the appended claims.

Referring to the drawings:

Fig. 1 is a side elevation of the magazine structure of a Linotype machine embodying the present improvements, the magazines being shown in their normal closed positions;

Fig. 2 is a view similar to Fig. 1, with some of the parts broken away, showing the magazines in a spread condition;

Fig. 3 is a sectional view, partly broken away, taken on the line 3—3 of Fig. 2, looking in the direction of the arrows;

Fig. 4 is a side elevation of the front portion of the bank of magazines, the parts being shown with the bottom magazine ready to be removed from the machine;

Fig. 5 is a top plan view, partly broken away, of a magazine base frame and associated mechanisms;

Fig. 6 is a sectional view taken on the line 6—6 of Fig. 5, looking in the direction of the arrows;

Fig. 7 is a transverse vertical section taken through a magazine in operative position, its base frame and associated parts; and

Fig. 8 is a vertical section, taken on the line 8—8 of Fig. 7, looking in the direction of the arrows.

The matrices are stored according to font in the superposed channeled magazines A, four of which are shown herein but of which a greater or less number might be employed, if desired (Fig. 1). The top magazine is of the split variety, i. e., it has lower and upper sections a and a^1 , the lower section a only containing matrices, and the upper section a^1 serving to guide the distributed matrices into the proper channels in the lower section. The remaining magazines are of the usual full length, both varieties of magazines being shown for purposes later to appear. The several magazines A are removably supported upon separate base frames A^1 con-

jointly constituting a shift frame which is arranged to be moved upwardly and downwardly in the fixed machine frame B to bring any selected magazine into operative relation to the assembling mechanism C at the lower end and the distributing mechanism D at the upper end. Each of the magazines is provided with a bank of matrix releasing escapements E which, when the magazine is brought into operative position, are actuated under the control of the keyboard mechanism in the usual way. The three upper base frames A^1 are pivoted at their upper ends, by pins A^2 , on a pair of plates A^3 , rising from the lowermost base frame at the opposite sides thereof, so that the base frames supporting the respective magazines may be spread apart to permit the independent removal of any selected magazine.

As best shown in Figs. 1 and 2, the banks of escapements E are mounted directly on the respective magazines. Such being the case, it is apparent that before a magazine can be removed from the machine, it must first be separated from its base frame sufficiently to enable the escapements to clear the assembling mechanism C. For this reason, each base frame is provided with a central magazine lifting and supporting plate F (see Figs. 4 and 5), which in the present instance is substantially as long in a fore-and-aft direction as the base frame itself, the plate being pivotally supported at its upper end in the base frame on pins F^1 , thus permitting it to be swung upwardly to lift the magazine. The plate F is formed with a central fore-and-aft groove F^2 which accommodates a correspondingly arranged reinforcing rib (not shown) on the underside of the overlying magazine. At its lower end, the plate F is provided with a stop shoulder F^3 which serves as an abutment to retain the magazine in place on the plate, when the latter is in its raised position, by engaging a transverse rib a^2 located as usual on the underside of the magazine near the front. The magazine lifting and supporting plate F, associated with each base frame, is raised and lowered by an underlying plate cam or equivalent device G fixed to a transverse rock shaft G^1 which is journaled in the base frame near the front end of the plate F (Figs. 4 and 5).

In the normal position of the parts, the magazine raising and lowering plate F is supported at its front end by the magazine base frame with the cam plate G located directly beneath it substantially in the plane of the base frame (see the magazine second from the bottom in Fig. 4). However, when the rock shaft G^1 is turned in a clockwise direction, looking at the machine from the left, the plate G will engage the underside of the plate F and cam the latter upwardly, thereby raising the magazine off its base frame to a position in which the escapements E on the magazine will clear the assembler throat C, thereby permitting the removal of the magazine (see the lower magazine in Fig. 4). On the other hand, when a replacement magazine has been located upon the plate F, a counterclockwise rotation of the rock shaft G^1 will restore the cam plate G to its normal position, permitting the magazine and the plate F, by gravity, but under the control of the cam plate G, to be restored to their normal positions on the base frame. It will be observed that the cam G is provided, on its active edge, with a hook shaped piece G^2 adapted, when the cam is turned upwardly, to engage a pin F^4 projecting from the

right edge of the overlying plate F and thus lock the latter in its proper raised position.

The transverse rock shafts G¹ have a common operating device which is automatically coupled to the corresponding shaft G¹ as the respective magazines are moved into operative position, it being recalled that a magazine must be so located before it can be removed from the machine. As shown in Figs. 4 to 8, the common device referred to includes in part, a rotatable member H supported in a bracket B¹ fixed to the machine frame B at the left of the bank of magazines and located in coaxial alignment with the rock shaft G¹ associated with the magazine in operative position. The member H is formed in its inner face with a groove H¹ which, in the normal position of the parts, extends in the direction of movement of the shift frame. At the left end of each rock shaft G¹, there is pinned a collar G³ formed with vertically spaced tongues G⁴ which align with the groove H¹ when the associated magazine is resting on its base frame. Consequently, as a magazine is raised or lowered into operative position by the movement of the shift frame, the tongues G⁴ on the associated rock shaft G¹ will enter the groove H¹ and couple the rock shaft and member H together. If the member H is now turned in a clockwise direction, looking at the parts from the left, the coupled rock shaft will likewise be turned in the same direction to raise the supporting plate F and lift the corresponding magazine off its base frame. And similarly, when a replacement magazine has been located on the elevated supporting plate F, the return movement of the member H to its normal position will lower such magazine into operative position on the supporting base frame as previously described.

The member H is rocked by a pivotally mounted magazine supporting arm K as the latter is swung from an inactive position alongside the shift frame to an active position in which it extends forwardly from the shift frame to support, in conjunction with a similar arm K¹ at the right side of the machine, the magazines as they are slid forwardly from their base frames (compare Figs. 1 and 4, and see Fig. 5). Normally, however, the arm K is prevented from being moved to its active position to effect the separation of the magazine in operative position from its supporting base frame until the magazines have been spread. The means for locking the arm K in its normal position are described later on. It will suffice to say here, that the means referred to are controlled by the magazine unit next above the magazine in operative position, the arrangement being such that unless the magazines have been spread, rotation of the magazine supporting arm K to operative position is prevented. When the magazines are spread, however, the locking means is rendered inoperative, leaving the magazine supporting arm K free to rotate.

The magazines are locked on their respective base frames, each by a pair of spring latches M pivotally mounted on the base frame to engage the opposite side edges of the magazine (Figs. 7 and 8). The latches M are controlled by a pair of cams G⁵, one formed on the collar G³, previously referred to, and the other on a collar G⁶, said collars being pinned to the rock shaft G¹ at its left and right ends, respectively. When the rock shaft G¹ is in its normal position, high portions G⁷ of the cams G⁵ hold the latches M in engagement with the magazine against the

action of latch springs M¹. However, when the shaft G¹ is rocked to separate the magazine from its base frame, its initial movement (which is idle as far as the separation of the magazine from its base frame is concerned) turns the cams G⁵ enough to move the high portions G⁷ thereof out of engagement with the latches, allowing the latch springs M¹ to rock the latches outwardly from the solid to the dotted line position shown in Fig. 7 where further movement is prevented by the engagement of the latches with low portions G⁸ of the cams. The latches are rendered inactive by the outward movement just referred to, thereby leaving the magazine free to be separated from its base frame by the further rotation of the rock shaft G¹. When a replacement magazine is lowered on to the base frame by the rocking of the shaft G¹ in the opposite direction, the high portions G⁷ of the cams G⁵ re-engage the respective latches M during the final rocking movement of the shaft and force the latches, against the action of the springs M¹, into locking engagement with the opposite sides of the magazine.

Except as hereinafter indicated, the mechanisms thus far described may be found in one or another of Patents No. 1,586,316 issued to McNamara and Nos. 1,860,868 and 2,157,795 issued to Mead.

Before describing the improved devices for rotating the rock shafts G by the magazine supporting arm K at the left of the machine, to raise the magazine in operative position clear of its base frame, reference will first be made to the mechanism for spreading the magazines, since, of course, that operation is the first to be performed.

Referring to Figs. 1, 2 and 3, it will be observed that below the bank of magazines, there is provided a transverse rock shaft N journalled in bearings B² located at opposite sides of the frame B, the shaft extending beyond the outer face of the bearing at the left to accommodate a crank N¹ which is pinned thereto. Adjacent each side of the magazine bank, there is provided a vertical arm N² formed at its lower end with an elongated slot N⁵ through which the shaft N passes, the arm N² resting, when in normal position, with the upper end of its slot bearing against the shaft. Each arm N² is connected to the shaft N by a toggle consisting of a crank arm N⁴ pinned to the rock shaft N and a link N⁶, the upper end of the latter being pivoted to the arm N² about midway of its length by a shouldered bolt N⁷, and the lower end of the link being pivoted at the end of the crank arm N⁴ by a shouldered screw N⁸.

Near their upper ends, the arms N² are formed on their front edges each with three spaced lugs N⁹, N¹⁰ and N¹¹, arranged one above the other, and adapted when the mechanism is operated to cooperate with lugs A¹⁸ projecting from the opposite sides of each of the three upper base frames.

The magazine spreading mechanism is held in its normal position, as shown in Fig. 1, by a spring clip N¹³ fastened to the machine frame at the right and which frictionally engages the crank handle N¹. Assuming now that the operator desires to spread the magazines in order to remove the one in operative position, he pulls forwardly on the arm N² until it banks against a stop N¹⁴ fixed in the machine frame. That movement of the crank N¹ rocks the shaft N in a clockwise direction, looking at the parts from the left, and during the first stage of its movement, the arms

N^2 rock forwardly with the shaft since, at that time, there is nothing to restrain them. However, when the arms N^2 reach the dotted line position shown in Fig. 1, their forward movement is arrested by the engagement of their front edges with the lugs A^{18} on the magazine base frames. Thereafter, the continued forward movement of the crank arm N^1 will straighten out the toggles (consisting of the small crank arms N^4 and the links N^6), with the result that the arms N^2 will be moved upwardly; and since the lugs N^9 , N^{10} and N^{11} are located so as to underlie the lugs A^{18} on the three upper base frames A^1 (assuming that the lowermost magazine is the one in operative position) when the forward movement of the arms N^2 is arrested, the three upper magazines and their base frames will be spread apart from the lowermost magazine to permit of its removal (Fig. 2).

The mechanism operates in a similar fashion when either the second or third magazine from the bottom is in operative position, the only difference being that when the second magazine is operative, the two lowermost lugs N^9 and N^{10} on the arms N^2 will cooperate with the lugs A^{18} of the two topmost magazines, the topmost lug N^{11} being idle; whereas when the third magazine from the bottom is in operative position, only the lowermost lugs N^9 on the arms N^2 will be active, the two topmost lugs N^{10} and N^{11} being idle.

It will be noted from Fig. 2 that when the arm N^1 is full forward resting against the stop N^{14} , the toggles have moved past the dead center position so that the weight of the magazines operates to prevent the counterclockwise rotation of the shaft N . In other words, once the magazines have been spread, they will thus remain until the operator restores them to normal position by an operation which is merely the reverse of that previously described, i. e., by a return movement of the handle N^1 to its normal position.

To prevent the separation of the arms N^2 from the lugs A^{18} , the lowermost lug N^9 is formed on its front edge and at the top with a lip N^{12} which, by engaging the lug A^{18} at the front, will counteract the tendency of the magazines, because of their weight, to cam the arms N^2 rearwardly. Only one set of lugs need be provided with such a lip, and it is appended to the bottom lugs N^9 since those lugs will always be operative when the spreading mechanism is used regardless of the magazine in operative position.

Due to the fact that the magazine base frames have their own individual pivots at the rear, those that are swung upwardly during a spreading operation will move relatively in a fore-and-aft direction. Accordingly, to permit this motion to take place freely without interference between the magazine units, provision is made for a progressive spreading of the magazines. Thus, assuming that the three upper magazines are to be spread to give access to the lowermost magazine, the spreading mechanism is so designed that the top magazine unit is moved up clear of the underlying unit before the latter starts to move, and the latter unit in turn is moved up clear of its underlying magazine before this last one starts to move.

To effect this progressive spreading movement of the magazines, the lugs N^9 , N^{10} and N^{11} on the arms N^2 , while spaced equidistantly as between themselves, are nevertheless spaced apart at greater distances than are the lugs A^{18} on the different magazine base frames when the latter are in their normal positions. Consequently, when

the arms N^2 are arrested in their forward movement by engagement with the lugs A^{18} , there will be just sufficient clearance between the parts to permit the top of the lugs N^{11} to pass freely beneath the overlying lugs A^{18} on the top base frame. The clearance between the intermediate lugs N^{10} and their overlying lug A^{18} will be greater, while the clearance between the lugs N^9 and their overlying lugs A^{18} will be greatest of all. Accordingly, as the arms N^2 are moved upwardly during the magazine spreading operation, they will pick up the magazine units progressively in order starting from the top. And, of course, when the magazine units are returned to their normal positions, they will seat one after another progressively starting with the bottom.

To complete the description of this phase of the invention, attention is directed to the fact that the arms N^2 are guided in their upward movement, on one side by the crank arms N^4 and, on the other side, by collars N^3 which, like the crank arms N^4 , are pinned to the shaft N (see Fig. 3).

After the magazines have been spread apart, the next step in the process of removing a magazine is to raise or separate it from its base frame so that its associated escapement mechanism E will clear the assembler throat C . As stated previously, this is accomplished by rotating the transverse rock shaft G^1 associated with the magazine in operative position, the shaft G^1 in turn rotating the cam plate G to raise the center plate F and consequently the magazine.

As previously stated, the shaft G^1 is rotated by the movement of the magazine supporting arm K into and out of its active position. It will be recalled that the rock shaft G^1 of the active magazine unit is automatically coupled by a tongue and groove connection to the member H as said magazine unit is brought into operative position (Fig. 7). The member H is in the form of a sleeve rotatably mounted on a shouldered screw H^3 threaded into the bracket B^1 , being formed at the right with the arm H^2 which presents the groove H^1 and at the left with an arm H^4 (Figs. 1 and 4). The arm H^4 is formed with an elongated slot H^{10} to accommodate a laterally extending pin H^9 presented at one end of a lever arm H^7 centrally fulcrummed as at H^8 and formed at its other end with a gear segment H^6 which meshes with a gear H^5 formed on the hub K^{15} of the magazine supporting arm K . At its free end, the magazine supporting arm K is equipped with a handle K^2 which may be grasped to move the arm into and out of its active position.

As previously stated, the movement of the arm K from its normal position is prevented unless the magazines have been spread. The means for the purpose includes the arm H^2 which, in the normal position of the parts, extends upwardly in the line of shift frame movement (Fig. 7). The free end of the arm H^2 is formed with an ear h^1 which extends laterally inward from the arm and normally lies behind the lowermost tongue G^4 on the collar G^3 fastened at the left end of the rock shaft G^1 on the base frame next above the magazine in operative position. Hence, before the magazines have been spread, any attempt to rotate the arm K to its active position is prevented by the engagement of the ear h^1 with the tongue G^4 . However, during the operation of spreading the magazines, the rock shaft G^1 on the base frame next above the magazine in operative position is carried upward so that the tongue

G^4 thereon will stand clear of the ear h^1 , leaving the arm K free to rotate.

Normally, the arm K extends rearwardly alongside the bank of magazines, and the arms H^4 and H^7 occupy positions at right angles to one another as shown in Figs. 1 and 2. However, as the arm K is swung forwardly into its active position, it operates through the gear H^5 and the gear segment H^6 to rotate the arm H^7 counterclockwise, looking at the parts from the left. The arm H^7 , in turn, through the medium of the pin H^9 thereon acting in the slot H^{10} on the arm H^4 , rotates the latter in the opposite direction to the position shown in Fig. 4. During the rotation of the arms H^7 and H^4 , the pin H^9 rides from the outer end of the slot H^{10} to the inner end thereof and return as the arms H^7 and H^4 move from the right angular relationship shown in Fig. 1 to the right angular relationship shown in Fig. 4. Such movement of the arm H^4 effects a corresponding movement of the member H to impart a 90° rotation in the same direction to the shaft G^1 , to raise the magazine from its base frame in the manner heretofore described, through the cooperation of the cam G and the plate F . When the replacement magazine has been located on the plate F , the magazine is lowered onto its base frame by a return movement of the arm K to its original inactive position, the operation of the interconnecting parts being the reverse of that just described.

With the foregoing arrangement, a 180° rotation of the arm K from inactive to active position is utilized to effect the 90° rotation of the shaft G^1 in separating the magazine from its base frame, thus obtaining a mechanical advantage of two. Additional mechanical advantage is obtained because of the formation of the plate cam G . Thus, the plate cam G is bent transversely to provide, at the bend, a portion g which, as the cam is rotated, first engages the plate F . As the cam G continues its rotation, the load is transferred to its extreme end g^1 to provide the necessary throw to complete the magazine separating movement. Hence, the arrangement provides a greater mechanical advantage to compensate for the shorter effective lever arm presented to the operator in the initial stages of movement, at which time, of course, the static inertia of the unit and friction between the confined banks must be overcome.

While the arm K for rotating the shaft G^1 could be of any suitable construction, it is proposed, in accordance with the present invention, to use it as one of a pair of arms for supporting the magazines at the front of the machine during the removal and replacement operations. To this end, the arm K is formed with a pair of ribs K^3 and K^4 projecting laterally different distances from its inner face, the lower rib K^4 projecting beyond the rib K^3 (Fig. 4). The ribs K^3 and K^4 converge at the hub end of the arm K into a single rib whose top surface lies slightly below the plane of the top surface of the plate F when the latter is in its raised position. The upper rib K^3 extends in the same plane throughout the length of the arm, terminating in an upturned lip K^5 . The rib K^4 , on the other hand, extends in the same direction as the rib K^3 but diverges downwardly therefrom, terminating short of the forward end of the arm K in an upturned lip K^6 whose free end is sufficiently below the rib K^3 so as not to interfere with a magazine supported on the latter rib. The companion arm K^1 at the opposite side of the bank of magazines is identically formed with ribs K^3 and K^4 .

The two pairs of ribs K^3 and K^4 adapt the

arms K and K^1 to support both full length magazines as well as the lower sections of the split variety of magazine, one of which, as stated, is shown as the top magazine in Fig. 1. Thus, in removing a full length magazine, such as the magazine shown in the raised removal position in Fig. 4, the magazine is lifted by hand to disengage the front transverse rib a^2 from the stop shoulder F^3 at the forward end of the plate F , freeing the magazine so that it can move forward by gravity guided by the central fore-and-aft reinforcing bar on its under surface riding in the groove F^2 in the plate F . As the magazine slides forward off the plate F , the rearmost transverse rib a^2 thereof comes to rest on the ribs K^3 and supports the magazine during the remainder of its travel until the rib a^2 strikes the lips K^5 , whence the magazine is allowed to pivot on the rib in assuming a vertical position from which it is manually lifted from the arms K and K^1 . In the replacement of a magazine, the rearmost transverse rib a^2 of the magazine is set on the ribs K^3 in back of the lips K^5 with the magazine in a vertical position. Then the magazine is tilted so that it lies substantially in the plane of the ribs K^3 and the plate F and is forced rearwardly until it reaches a position where its forward end can be lowered on to the plate F with the foremost transverse rib a^2 thereof engaged behind the shoulder F^3 . The magazine is then in position to be lowered onto its supporting base frame.

With the split variety of magazine, however, the rearmost transverse rib a^2 is not as long (due to the divergent shape of the magazines) as the rearmost transverse rib of a full length magazine. Hence, when the section a is removed (in the same manner as already set forth for a full length magazine) its rearmost rib a^2 slides along the wider ribs K^4 and comes to rest against the lips K^6 thereof, where it is pivotally supported in a vertical position prior to being lifted from the arms K and K^1 .

The magazine supporting arm K^1 , at the right of the machine, is movable into and out of active position independently of the arm K . As shown in Figs. 5 and 6, the arm K^1 is pivotally mounted on a stub shaft K^7 fastened by a nut K^8 to the frame B so that, like the arm K , it extends rearwardly alongside the bank of magazines when in its inactive position and is provided with a handle K^9 whereby it may be rocked manually into and out of its forward active position. Because the right side of the magazines do not diverge outwardly from front to rear to the same extent as the left side of the magazines (see the shape of the base frame in Fig. 5), and also in order that the arm K^1 will clear the bank of magazines when in its inactive position and yet be in magazine supporting position when in its active position, the arm K^1 is fastened to the shaft K^7 by a screw K^{10} extending through a hub portion K^{11} of the arm and having a reduced unthreaded end portion K^{12} which projects into a spiral groove K^{13} formed in the periphery of the shaft and extending throughout one-half the circumference thereof (Fig. 6). With this arrangement, when the arm K^1 is moved from the full line position to the dotted line position in Fig. 5, the screw K^{10} follows the spiral groove K^{13} and shifts the arm K^1 as a whole inwardly or to the left toward the companion arm K , the screw K^{10} maintaining the arm K^1 in its active position by banking against the end of the slot K^{13} . Likewise when the arm K^1 is returned to its inactive position, the end of the screw K^{10} follows the groove K^{13} and shifts

the arm as a whole outwardly or to the right, coming to rest in its inactive position as the screw K¹⁰ banks against the opposite end of the groove K¹³.

Coming now to the individual magazine supporting base frames A¹, these are formed of steel structural elements welded together into a unitary structure (Fig. 5). Each base frame comprises a pair of side structural angle members A⁴ which extend between and are welded to a front channel member A⁵ and a rear bar or plate A⁶. Two centrally located, spaced-apart structural angle members A⁷, extend in parallel relation between and are welded to the front channel member A⁵ and the rear bar A⁶. A U-shaped member A⁸, for supporting the magazine separating plate F, is arranged flatwise with its cross-bar welded to the under side of the rear bar A⁶, its arms extending forwardly and being welded to the center members A⁷. Hence, the base frame is a simple built-up structure of light-weight steel structural elements which may be individually machined, where machining is necessary, before being assembled and welded into a unit.

The rear bar A⁶ of the base frame is equipped at its opposite ends with the pins A², previously mentioned, which engage in notches formed in the side plates A³ to permit the pivotal movement of the base frame in the spreading of the magazines. A cut-out A¹⁵ is provided in the forward edge of the rear bar A⁶ to receive the aforementioned centrally located fore-and-aft reinforcing bar on the underside of the magazine. The U-shaped member A⁸, which supports the rear end of the magazine separating plate F, has grooves A¹⁶ formed in the top surface of its two arms to provide bearings for the pins F¹ projecting from opposite sides of the plate and which permit the pivotal movement of the plate in raising and lowering the magazine. In order to provide clearance for the plate F and cam G when in their inactive positions, so that the magazine will rest on the side members A⁴ of the base frame, both the front and rear walls of the channel member A⁵ are cut away as at A¹⁷.

Two members A²⁵ are welded to the channel member A⁵ at its opposite ends and extend forwardly therefrom, being formed at their front ends with upstanding shoulders or lugs A¹⁰ adapted to engage the forward edge of the front magazine cross bar a² to hold the magazine in position on the base frame. A boss A¹¹ is formed on the outer face of each of the members A²⁵, and each boss is drilled through from top to bottom and threaded to accommodate banking screws A¹² and A¹³ for the adjustment and location of the base frames to support the respective magazines in proper registry with the assembling mechanism C when in operative position. As best shown in Figs. 1 and 8, the banking screws A¹³ are threaded up tight against the bottom of the bosses A¹¹, whereas the screws A¹² in the respective base frames are threaded downwardly into the bosses, the screws A¹² being long enough to extend above the top of the magazines supported on said base frames into engagement with the banking screws A¹³ of the base frame next above. The banking screws A¹² are secured in their positions by adjusted lock nuts A¹⁴. This arrangement eliminates all the machining that otherwise would have to be performed on the base frames themselves were surfaces thereon used in effecting the base frame adjustment.

To complete the description of the base frames, 75

it will be noted that both of the members A²⁵ are formed with thickened portions A¹⁹ which extend inwardly into the opposite ends of the front channel member A⁵ as well as outwardly beyond the side faces of the members A⁴ to form bosses A²⁰. In the region of the thickened portion A¹⁹, the members A²⁵ are drilled to provide holes A²¹, through which the rock shaft G¹ extends. The collars G³ and G⁶ pinned to the shaft G¹ are formed with shanks G⁸ which fit into the holes A²¹ and provide bearing surfaces for the shaft. The outwardly extending bosses A²⁰ are formed each with a pair of spaced apart ears A²² drilled to accommodate a pin A²³ on which the latches M are pivoted, and the bosses are drilled to provide sockets A²⁴ which accommodate each one end of the respective compression spring M¹, the opposite end of which extends into a recess M² formed in the associated latch M.

In the assembly of the rock shaft G¹ on the base frame A¹, one collar, say the collar G⁶, is detached from the shaft and the latter is threaded through the holes A²¹ from left to right until a shoulder G⁹ on the collar G³ banks against the outer face of the left-hand member A²⁵, whereupon the collar G⁶ is slipped on and pinned to the opposite end of the shaft with its shoulder G⁹ banking against the outer face of the right-hand member A²⁵.

It will now be apparent that the present invention represents a distinct advance over the construction of the present commercial machine. The improved base frame is structurally a more simplified unit, and this, in addition to the fact that the elements are structural shapes, enables a reduction in the weight of the base frame structure equal to approximately one-half the weight of a standard cast iron base frame. Yet such reduction in weight carries with it no sacrifice in strength. The substantial reduction in the weight of the shift frame unit has resulted in cutting down the time required for the magazine shifting operation due to the fact that the shift unit can be accelerated and decelerated with less effort and clash. Furthermore it permits a more satisfactory counterbalancing of the shift frame unit and reduces the possibility of damage to the parts in the event something intervenes to obstruct its movement.

Because of their size, the individual elements making up the improved base frame are much easier to handle for machining and finishing, and should one element be accidentally rendered unusable, that element alone is affected. Moreover, the individual elements, and the base frame as a whole, being made of steel, have more life and are tougher than the cast iron structure of the art. While it is preferred to use steel structural elements and weld them into a unitary structure, obviously the elements could be made of other materials or alloys having the desired characteristics of adequate strength and light weight; and in any case, the elements could be joined together otherwise than by welding.

As regards the improved magazine spreading and separating mechanisms, here again simplicity of design and construction are combined in providing for rapid and easy operation. The magazine spreading mechanism is mounted in the machine frame as rotation of the magazine supporting arm to obtain the increase in mechanical advantage as set forth.

Other features and advantages, too numerous to set forth herein, will be obvious to those skilled in the art, and, as already stated, many variations

and modifications of the preferred embodiment of the invention shown in the accompanying drawings may be made which will still be comprised within its spirit. It is to be understood, therefore, that the invention is not to be limited to any particular form or embodiment except insofar as such limitations are specified in the appended claims.

Having thus described my invention, what I claim is:

1. A typographical machine including, in combination, a plurality of matrix magazines, a shift frame therefor comprising a plurality of base frames upon which the respective magazines are removably supported, said shift frame being movable to locate a selected magazine in operative position, and magazine spreading mechanism mounted in a fixed part of the machine frame independently of the shift frame and operable to cooperate with the base frames above the magazine in operative position to separate them from said magazine.

2. A combination according to claim 1, wherein in each base frame is equipped with lugs projecting from its opposite side edges, and wherein the magazine spreading mechanism includes a pair of vertical arms arranged one at each side of the shift frame and movable to engage the lugs on the base frames above the magazine in operative position for lifting the respective base frames to separate them from said magazine and provide clearance for its removal.

3. A combination according to claim 1, wherein each base frame is equipped with lugs projecting from its opposite side edges, and wherein the magazine spreading mechanism includes a pair of vertical arms arranged one at each side of the shift frame and movable to engage the lugs on the base frames above the magazine in operative position for lifting the respective base frames to separate them from said magazine and provide clearance for its removal, the arms being provided with a plurality of lug engaging members and the magazines to be lifted being determined by the position of the shift frame according to the magazine selected.

4. A combination according to claim 1, wherein the magazine spreading mechanism includes arms movable from an inoperative position into cooperative engagement with the base frames above the magazine in operative position and toggle instrumentalities connected to said arms and operable first to move the arms into said cooperative engagement with the base frames and then to straighten out, thereby to move the arms in a manner to separate the base frames from the magazine in operative position.

5. A combination according to claim 1, wherein the magazine spreading mechanism includes devices arranged to act progressively, starting from the base frame at the top, to separate them from the operatively positioned magazine.

6. A typographical machine including, in combination, a plurality of matrix magazines, a shift frame therefor comprising a plurality of base frames upon which the respective magazines are removably supported and which are provided with lugs projecting from their opposite side edges, said shift frame being movable to locate a selected magazine in operative position, a transverse rock shaft mounted in a fixed part of the machine frame beneath the shift frame, a pair of arms carried by the rock shaft and arranged to extend vertically alongside the shift frame in laterally spaced relation thereto, a series of lugs

located on said arms and adapted to engage the lugs on the base frames above the magazine in operative position, the arms normally occupying a position rearward of the lugs on the base frames, a crank for rotating said shaft, and means for imparting a compound movement to said arms in response to the rotation of said shaft to cause them first to move forward into engagement with the lugs on the respective base frames and then to move upward to bring the lugs thereon into engagement with the lugs on said base frames and lift the latter to separate them from the magazine below.

7. A combination according to claim 6, wherein said arms are formed with elongated slots through which the rock shaft passes and are connected each by a link to a crank arm fast to the shaft.

8. In a typographical machine equipped with a plurality of matrix magazines removably mounted on individual base frames having devices for lifting the magazines from their respective base frames for removal, the combination of a pivoted magazine supporting arm, a pinion mounted for rotation conjointly with said arm, a pivoted arm formed at one end with a gear segment arranged to mesh with said pinion and provided at its opposite end with a laterally projecting pin, a rotatable sleeve, an arm formed on the sleeve and slotted to receive said pin, and a second arm formed on the sleeve and operative normally, by cooperation with means associated with an adjacent magazine, to prevent the magazine separating movement of said magazine supporting arm.

9. A typographical machine according to claim 8, wherein the base frame above the magazine to be removed is adapted to be lifted to provide clearance for the separation of said magazine from its base frame, and wherein said second arm on the sleeve is operative to prevent the magazine separating movement of said supporting arm until the overlying base frame has been lifted.

10. In a typographical machine equipped with a plurality of matrix magazines removably mounted on individual base frames, the combination of a bracket secured to the machine frame, a magazine supporting arm formed at one end with a hub portion by which it is pivotally mounted on a shaft supported in said bracket, a pinion arranged on the hub portion of said supporting arm, an arm pivotally mounted in said bracket and formed at one end with a gear segment arranged to mesh with said pinion and provided at its opposite end with a laterally projecting pin, a sleeve rotatably mounted in said bracket and formed with an arm slotted to receive said pin, the sleeve being adapted to be rotated by the movement of the magazine supporting arm into active position, means on the sleeve for coupling it to mechanism adapted to be actuated by the rotation of the sleeve to separate the magazine from its base frame for removal, and a second arm on said sleeve arranged to cooperate with the base frame above the magazine to be removed to prevent the magazine separating movement of said supporting arm until said latter base frame has been lifted out of its normal position.

11. In a typographical machine equipped with a plurality of matrix magazines removably mounted on individual base frames having devices for lifting the magazines from their respective base frames for removal, the combination of a pivotally mounted magazine supporting arm movable from an inoperative to an operative po-

sition, means actuated by such movement of the magazine supporting arm for actuating the lifting devices of the magazine in operative position to separate said magazine from its base frame, mechanism for spreading the magazines preparatory to such actuation of the magazine lifting devices, and safety means to prevent the movement of the magazine supporting arm until after the magazine spreading mechanism has been operated.

12. In or for a typographical composing machine equipped with a plurality of superposed matrix magazines supported on individual base frames constituting a shift frame movable to bring any selected magazine into operative position, the combination of means for pivotally mounting the base frames adjacent their rear ends in the shift frame in proper spaced relation, and means acting entirely independently of the magazines for properly spacing the base frames adjacent their front ends in normal nested relation.

13. In or for a typographical machine adapted to be equipped with removable matrix magazines, a pair of pivoted arms for supporting the magazines during removal and arranged one at each side of the machine, said arms being adapted to be rocked forward and rearward into and out of active position, one of said arms being mounted to move axially on its pivot toward and away from the companion arm during such forward and rearward movements, respectively.

14. In or for a typographical machine adapted to be equipped with removable matrix magazines, a pair of pivoted arms for supporting the magazines during removal and arranged one at each side of the machine, said arms being adapted to be rocked forward and rearward into and out of active position, one of said arms being mounted on a shaft formed with a spiral groove adapted to receive the end of a pin fixed in the arm hub, whereby an axial movement is imparted to the arm during its rocking movements.

15. In or for a typographical machine, a magazine base frame built up of a plurality of prefabricated steel structural shapes and comprising a front channel member and a rear bar connected by side members of right angular cross-section welded thereto, a pair of spaced-apart centrally located members of right angular cross-section extending fore-and-aft in parallel relationship between said front channel member and rear bar and being welded thereto, a U-shaped plate arranged flatwise with its cross-bar welded to the underside of said rear bar and its arms extending forward between and welded to said centrally located members, and a shouldered support extending forward beyond said front channel member at each side of the base frame for holding a magazine thereon.

16. A magazine base frame according to claim 15, including a magazine supporting plate pivoted at its rear end on said U-shaped plate and extending forward between said centrally located members to overlie the front channel member and extending beyond the forward edge thereof, a rock shaft arranged in the front channel member, and a cam element arranged below said supporting plate and actuatable by the rocking of said shaft to raise and lower the supporting plate.

17. A combination according to claim 12, wherein the spacing means include adjusting screws threaded into the base frames at opposite sides thereof and adapted to contact with banking surfaces on an adjacent base frame.

18. A combination according to claim 12, wherein the spacing means include screws threaded into the base frames at opposite sides thereof and adapted to contact with banking surfaces on an adjacent frame, said banking surfaces being presented by screws threaded into said adjacent frames.

19. A combination according to claim 1, wherein each base frame is equipped with lugs projecting from its opposite side edges, and wherein the magazine spreading mechanism includes a pair of vertical arms arranged one at each side of the shift frame and movable to engage the lugs on the base frames above the magazine in operative position for lifting the respective base frames to separate them from said magazine and provide clearance for its removal, the arms being provided with a plurality of lug engaging members and the magazines to be lifted being determined by the position of the shift frame according to the magazine selected, and the spacing of said lug engaging members being greater than the normal spacing of the lugs on the base frames, whereby as the arms partake of their spreading movement the lug engaging members will act upon the lugs on the base frames progressively, starting from the top.

20. A combination according to claim 1, wherein each base frame is equipped with lugs projecting from its opposite side edges, and wherein the magazine spreading mechanism includes a pair of vertical arms arranged one at each side of the shift frame and movable to engage the lugs on the base frames above the magazine in operative position for lifting the respective base frames to separate them from said magazine and provide clearance for its removal, the arms being provided with a plurality of lug engaging members and the magazines to be lifted being determined by the position of the shift frame according to the magazine selected, and the lower-most lug engaging members on the arms being equipped with means for preventing their disengagement from the lugs on the corresponding base frame during the magazine spreading operation.

21. A combination according to claim 1, wherein the magazine spreading mechanism includes arms movable from an inoperative position into cooperative engagement with the base frames above the magazine in operative position and toggle instrumentalities connected to said arms and operable first to move the arms into said cooperative engagement with the base frames and then to straighten out, thereby to move the arms in a manner to separate the base frames from the magazine in operative position, said toggle instrumentalities when straightened out being located in a past dead center position so as to sustain the magazines in their spread condition.

22. In or for a typographical machine equipped with a matrix magazine supported on a base frame having devices for lifting the magazine off its base frame to facilitate its removal, said lifting devices including a rotatable shaft, the combination of a pivotally mounted magazine supporting arm movable from an inoperative to an operative position, and mechanism actuated by such movement of the magazine supporting arm for operating said magazine lifting devices, said mechanism including a pinion meshing with a gear segment formed on one end of a pivoted arm whose opposite end is connected to a crank arm for rotating said shaft.

23. In or for a typographical machine equipped with a matrix magazine supported on a base frame having devices for lifting the magazine off its base frame to facilitate its removal, said lifting devices including a rotatable shaft, the combination of a pivotally mounted magazine supporting arm movable from an inoperative to an operative position, and mechanism actuated by such movement of the magazine supporting arm for operating said magazine lifting devices, said mechanism including a pinion meshing with a gear segment formed on one end of a pivoted arm whose opposite end is connected to a crank arm for rotating said shaft, the crank arm being slotted to receive a pin projecting laterally from the end of said pivoted arm, said pin being arranged to move from one end of the slot to the other and return during the adjustment of the magazine supporting arm to operative position.

24. In or for a typographical machine equipped with a matrix magazine supported on a base frame having devices for lifting the magazine off its base frame to facilitate its removal, said lifting devices including a rotatable shaft, the combination of a pivotally mounted magazine supporting arm movable from an inoperative to an operative position, and mechanism actuated by such movement of the magazine supporting arm for operating said magazine lifting devices, said mechanism including a pinion meshing with a gear segment formed on one end of a pivoted arm whose opposite end is connected to a crank arm for rotating said shaft, the crank comprising an arm formed on one end of a rotatable sleeve provided at its opposite end with means for coupling it to said shaft.

25. In a typographical machine, the combina-

tion of a pair of matrix magazines removable endwise in a forward direction, said magazines being of different widths, and a pair of inclined magazine supporting arms common to both magazines, said pair of magazine supporting arms being formed on their inner faces each with two longitudinally extending ribs of different widths to give support to the individual magazines during forward removal, the ribs of lesser width serving for the magazine of greater width, and the ribs of greater width serving for the magazine of lesser width.

26. A combination according to claim 25, wherein the magazine supporting ribs of lesser width are disposed substantially in the plane in which the wider magazine is removed, while the magazine supporting ribs of greater width are disposed at an angle to the plane in which the narrower magazine is removed.

27. A combination according to claim 25, wherein the magazine supporting ribs of lesser width are disposed substantially in the plane in which the wider magazine is removed, while the magazine supporting ribs of greater width have their inner ends disposed in said plane but diverging downwardly therefrom toward their outer ends to provide a trackway at a different level for the narrower magazine.

28. A combination according to claim 25, wherein the magazine supporting arms are formed at the outer extremities of each pair of magazine supporting ribs with upturned lips for engagement with protruding portions of the magazines, whereby said magazines may be suspended in a vertical position upon the magazine supporting arms in the course of removal.

JAMES C. PLASTARAS.
